W. A. E. MADDOCK

AIR RELEASE DEVICE

Filed April 14, 1921

INVENTOR
W. A. E. MADDOCK,
BY *Mem. Des.*
ATTORNEYS

UNITED STATES PATENT OFFICE.

WALTER A. E. MADDOCK, OF HAMILTON, NORTH DAKOTA.

AIR-RELEASE DEVICE.

Application filed April 14, 1921. Serial No. 461,214.

To all whom it may concern:

Be it known that I, WALTER A. E. MADDOCK, a citizen of the United States, and resident of Hamilton, in the county of 5 Pembina and State of North Dakota, have invented certain new and useful Improvements in Air-Release Devices, of which the following is a specification.

This invention relates to air releasing devices especially adapted for use in connection with pneumatic tires.

Briefly stated, an important object of this invention is to provide an air release device having simple means whereby the same may 15 be readily attached to a valve stem for unseating the valve, and thereby permit air to escape from the tire.

A further object is to provide an air releasing device which is of highly simplified 20 construction, durable in use, and cheap to manufacture.

Other objects and advantages of the invention will be apparent during the course 25 of the following description.

In the accompanying drawing:

Figure 1 is a perspective view of the device applied.

Figure 2 is a vertical sectional view through the same applied.

Figure 3 is a detail longitudinal sectional view through a slight modification of the 30 invention.

In the drawing, the numeral 5 designates the valve stem of a tube 6, the said tube being located within a casing 7.

The improved air releasing device consists of an exteriorly knurled tubular body 9 having its forward portion interiorly threaded for threaded engagement with the 40 terminal portion of the valve stem 5. It will be seen with reference to Figure 2 that a cone-shaped head 11 is arranged within the tubular body 9 at a point spaced rearwardly of the forward end thereof and the 45 forward pointed end of the cone-shaped head 11 is adapted to engage the valve 14 so as to unseat the same.

Figure 2 illustrates that the rear portion of the cone-shaped head 11 and the adjacent 50 portion of the tubular body 9 are provided with inwardly pressed interfitting annular beads 16 and 17 respectively by means of which the head 11 is securely held in position.

In operation, the tubular body 9 is threaded on the stem 5 and the pointed forward

end of the cone-shaped body 11 is engaged with the valve 14 so as to unseat the same, whereupon the air passes through the perforations 20 and through the tubular body 9. 60

The rear portion of the tubular body is reduced in cross sectional area to form a narrow outlet opening 25 for the air and as the opening 25 is considerably smaller than the bore of the tubular body 9 foreign 65 matter cannot freely enter the tubular body by way of the opening 25.

In the form of the invention illustrated in Fig. 3, the tubular body which is designated by the numeral 40, has its forward portion interiorly screw-threaded, as indicated at 41, for engagement with the rear portion of the valve stem. In this form of the invention the head 44 has its forward end formed with a wall having its central 70 portion provided with a cone-shaped extension 47 adapted for engaging the valve, whereby to unseat the same. In this case the cone-shaped extension 47 is surrounded by a series of apertures 48 through which 80 the released air travels.

Figure 3 also illustrates that the head 44 and the tubular body 40 are formed with interfitting annular beads 49 and 50, respectively, by means of which the head is 85 securely held in position.

With reference to the foregoing description taken in connection with the accompanying drawing, the highly simplified construction and utility of this invention will 90 be apparent.

Having thus described my invention, what I claim is:—

As an article of manufacture, an air releasing device for tire valves comprising a 95 tubular body having its forward portion interiorly threaded for engaging the threads of a valve stem, a cone shaped perforated head fitted in the forward portion of said body at a point spaced from the screw threads and having a pointed forward end for engaging and depressing the valve, the rear portion of said head and adjacent portion of the tubular body being formed with inwardly pressed interfitting annular beads 100 forming an attaching means for the head, the rear portion of the tubular body being reduced in cross sectional area to form a small air outlet opening, and to prevent foreign matter from freely entering the tubular body. 105

WALTER A. E. MADDOCK.
